CLAIM

The ornamental design for an electric dryshaver, substantially as shown and described.

DESCRIPTION

FIG. 1 is a front elevational view of an electric dryshaver showing my new design, the continuous textures of the body and shaving head being shown only partially for convenience of illustration.

FIG. 2 is a rear elevational view thereof;

FIG. 3 is a right-side view thereof;

FIG. 4 is a left-side view thereof;

FIG. 5 is a top plan view thereof;

FIG. 6 is a bottom plan view thereof; and

FIG. 7 is a left front perspective view of the dryshaver shown in FIG. 1.
